INDOOR TELEVISION ANTENNA

John D. Callaghan, Cherry Hill, N.J., assignor to Radio Corporation of America, a corporation of Delaware

Filed Sept. 7, 1966, Ser. No. 3,759

Term of patent 14 years

(Cl. D26—14)

FIGURE 1 is a front elevational view of the indoor television antenna; and

FIGURE 2 is a side elevational view of the indoor television antenna of FIGURE 1.

I claim:

The ornamental design for an indoor television antenna, substantially as shown and described.
